UNITED STATES PATENT OFFICE.

SYDNEY M. TRAUBITZ, OF NEW YORK, N. Y.

ELECTRICAL OUTLET.

Application filed November 16, 1927. Serial No. 233,602.

This invention relates to a device known as an electrical convenience outlet, the same being adapted to be used as an auxiliary device in connection with the regular house wiring, 5 permitting an outlet to be located wherever desired. It is particularly useful for attachment on the baseboards of rooms or other parts of the house to suit the requirements of the individual.

10 The object of the invention is to provide a simple and completely safe device of this character which may be readily secured in position and thereafter wired without difficulty and without in any way cutting or mar- 15 ring the base to which it is secured.

A further object of my invention is to provide an article of this kind which will have several uses, permitting it to be interchangeably used as an electrical outlet and also as a 20 connection plug for the various electrical devices commonly employed in household use.

25 With these objects and such other objects as may hereinafter appear, in view, I have devised the particular embodiment described below and more particularly pointed out in the claims appended hereto.

Reference is to be had to the accompanying drawing, forming a part hereof, in which

30 Figure 1 is a plan view of my improved electric outlet;

Figure 2 is a similar view of the base of the outlet showing the contacts thereon and the wire-receiving grooves;

35 Figure 3 is a vertical sectional view of the parts shown in Figure 2 showing the same secured to a support;

40 Figure 4 is a side elevation of the complete device with the cover or cap being shown in cross-section and parts of the base being broken away to disclose construction;

Figure 5 is a sectional view on the line 45 5—5 of Figure 3, looking in the direction of the arrows; and

Figure 6 is a side elevation partly in section of a modified structure showing the manner in which the outlet may be secured to a metal strip which may be attached to a support or in an outlet box.

Throughout the various views of the drawings, 50 similar reference characters designate similar parts.

In the embodiment of my invention disclosed in the accompanying drawing, 1 indicates the body portion of the device. The 55 same is preferably made of any suitable insulating material, such as hard rubber, mica,

porcelain or the like. It comprises a disk-shaped base portion 2 having a flat rear surface 3 enabling it to be placed against a baseboard or other article to which it is to be secured as shown at 4 in Figure 3. The base portion 2 is preferably made of substantial thickness and its upper surface is provided with a plurality of grooves 5 and 6. The two grooves 6 are preferably placed diametrically opposite one another on the base and are of sufficient depth to receive the wiring 7 (Figure 5). If desired, perforations 8 may be located in said grooves 5 through which screws or other fastening means may be used 70 to secure the body portion to a support such as 4.

The grooves 6 receive spring contact fingers 9 which extend upwardly on opposite sides of an outstanding projection 10 which forms an integral part of the base 2. This part 10 is provided with an enlarged head 11 which has a pair of oppositely disposed slots 12 in which upwardly extending parts 13 of the spring contacts 9 extend. Said spring 80 contacts have their lower ends secured in the grooves 6 by means of tubular rivets 14, which rivets are internally threaded so that the same may receive screws 15 which act as binding posts for the wiring 7 as is disclosed 85 in Figure 5.

The head 11 is externally threaded as at 16 and an internally threaded closure cap or cover 17 is received on said head and when threaded down as disclosed in Figures 4 and 90 6, it covers the contacts 14, the spring fingers 9 and the grooves 5. It will be seen that the head 11 is under-cut as at 18 to provide a circumferential groove or space 19 located between the under-side of the head 11 and the 95 upper face of the base 2. This groove is completely closed as disclosed in Figure 4 by the cap 17 so that the divided wires are thus held within this closed space and are neither visible nor accessible when the cover 17 is 100 placed in position. It will be seen that the top of said cover is provided with a pair of slots 20 which register with the parts 13 on the spring fingers 9 permitting the prongs on the conventional type of connection plug to 105 enter through said slots 20 and establish connection with the fingers 9.

I have also shown the body portion 1 provided with a continuous central perforation 21 through which a securing screw 22 may 110 pass to secure the device to a base or other support. It will be seen that when the de-

vice is so attached and the cover member or cap 17 is in place, the securing screw 22 is completely covered and rendered invisible. Any other means of securing the device in 5 position supplementary to screws which can pass through the perforations 8 and 21 may be used if desired.

In Figure 6 a modified structure is shown, wherein I have shown the base portion 2 of 10 the device secured to a metallic strap 22 by means of a tubular rivet 23. The strap 22 is provided with perforations 24 at its ends so that the same can be secured to any suitable support or in an outlet box or the like. The 15 strap may also be varied in shape to suit different requirements.

I have heretofore described my device as being used for an electrical outlet primarily intended to be secured to a base or other fixed 20 support. It is however, readily useful as a connection plug by merely securing it to the ends of a lead wire as shown and not securing it in any way to a fixed support, the usual connection being established to a wire 25 leading from a source of current by means of a two pronged plug which connects through the slots 20 in the cover member in the conventional way.

A feature of the invention also resides in 30 the fact that when the device is used as a fixed outlet member, it may be secured to a support and thereafter wired, enabling the wire to be done neatly and more expeditiously than is the case where the device must be first 35 wired and then secured in position.

It will be seen that the base portion 2 of the device is provided with two oppositely disposed grooves 5.

In cases where the wiring is to pass completely through the outlet device, the wiring 40 first enters through one of the grooves 5 where it is separated, bared and connected to the contact screws 15 and thereafter continues out through the other groove 5.

45 The device has many uses, several of which have been herein set forth.

Having described one embodiment of my invention, it is obvious that the same is not to be restricted thereto, but is broad enough to 50 cover all structures coming within the scope of the annexed claims.

What I claim is:

1. An electric outlet comprising a body portion having an opening extending 55 through it for receiving securing means, a flat base on said body portion having a grooved upper face, spring contact fingers secured in and extending out of several of said grooves, an integrally formed slotted pro-

jection extending from said base, said projection having an enlarged threaded head, and an internally threaded cap adapted to be received on said head and cover the upper face of the base and the contact fingers thereon. 60

2. An electric outlet having a base member, 65 said base member having a flat inner part adapted to be secured against a support, a pair of wire-receiving grooves in the upper face of said base, a pair of spring contacts secured on said base and extending outwardly therefrom, a slotted projection on said base, a threaded outer terminal on said projection and a cap adapted to fit over said projection and be received on the threaded part thereon, and cover the contacts and grooves. 70 75

3. An electric outlet having a flat base, an off-standing projection thereon, an enlarged head on the outer end of said projection forming a groove between its inner end and the outer face of the base, contact screws on said base, spring contact fingers connected thereto, parts on said fingers extending from the base, slots in the enlarged head into which said extended parts on the fingers project, a closure cap adapted to be received over and held on the enlarged head, said cap extending over and covering the contacts and spring fingers, and openings in said cap permitting access to the spring fingers. 80 85

4. An electric outlet comprising a body portion having a base, contacts on said base, spring fingers connected thereto, a slotted outstanding projection on the base disposed between the spring fingers, said fingers located in the slots in the projection, a cover member adapted to fit over the projection and enclose the contacts and the spring fingers, and openings in the cover in registration with the spring fingers to permit contact with said fingers to be made by prongs inserted through said openings. 90 95

5. An electric outlet having a flat base, means for securing the same to a support, a threaded plug-like extension projecting from the face of said base, slots therein, contacts on the base on opposite sides of the plug-like extension located in the slots in said extension, an apertured cover member received on and held by the plug-like extension, the apertures in said cover member being adapted to align with the contacts to permit the entry of pronged members on a connection plug for establishing contact between said members and the contacts. 100 110 115

Signed at the city, county and State of New York, this 15th day of November, 1927,

SYDNEY M. TRAUBITZ.
